Mrs. P. Breckenridge

United States Patent Office.

MOSES P. BRECKENRIDGE, OF MERIDEN, CONNECTICUT.

Letters Patent No. 84,674, dated December 8, 1868.

SELF-REGULATING AIR-VALVE FOR STEAM-HEATERS.

The Schedule referred to in these Letters Patent and making part of the same.

To all whom it may concern:

Be it known that I, MOSES P. BRECKENRIDGE, of Meriden, county of New Haven, and State of Connecticut, have invented a new and useful Improvement in Self-Regulating Air-Valves; and I do hereby declare the following to be a full, clear, and exact description of the same, reference being had to the accompanying drawings, and to the letters of reference marked thereon.

Said drawings constitute part of this specification, and represent, in—

Figure 1, a side view of my improved valve; in Figure 2, a longitudinal section of the same; and in Figure 3, the inside frame, removed from the cylinder.

Similar letters of reference, when they occur in the separate views, indicate like parts.

My invention relates to an improvement in self-regulating air-valves for steam-radiators, and consists of a cylinder, cast in one piece, and cored in the centre for the reception of a frame, in which a spring, similar to that in common use for the same purpose, is securely held at each end.

The centre of this spring is connected by means of a screw with a vent-plug or valve, which valve, as the steam acts upon the spring, is drawn down upon its seat, and made perfectly steam and water-tight.

It is well known that in steam-heating the cold air must first be expelled from the pipes, in order that the steam may flow freely therein, to automatically expel the air, and not allow the steam to escape.

My invention is calculated, and its advantage over others of a similar nature is in making the cylinder in one piece, and inserting at one end the frame holding the spring, thus avoiding the use of packing, and making a perfectly tight valve, which is extremely difficult to obtain for any length of time in the valves now used, in which the cylinder is made in two parts, the steam, acting upon the packing, soon rendering it pervious and liable to leak.

There being no more work upon my valve than upon the ordinary kind, it can be made fully as cheap.

To enable others skilled in the art to make and use my invention, I will proceed to describe the construction and operation of the same.

A is a cylinder, cast in one piece, either round or octagonal in form, and bored out in the centre to any given size for the reception of the frame B, which is constructed with projections, *a a*, at each end, between which projections a spring, C, is securely held.

About midway between the two ends, upon the circumference of the cylinder, a valve-seat, b, is formed, into which a valve, D, is fitted.

This valve D is connected, by means of the screw E, (which passes through a slot in the frame B,) with the spring C.

The frame B is held in its place in the cylinder A, by means of a set-screw, c, and the cylinder A is provided with a screw-thread, d, by which means it is connected with the pipes or radiator.

This completes the construction of my invention. The operation is as follows:

The frame B is first inserted in the case or cylinder A. The said cylinder is then screwed upon the pipe connected with the radiator, or directly with the boiler. The valve is opened or set, so that there shall be a space between it and the seat, through which the air may pass.

The air will pass freely through this opening, until it is all ejected from the pipe.

The steam, which follows it up, immediately fills the case or cylinder A.

The heat of the said steam, acting upon the spring C, causes it to expand, and, as the ends are held perfectly firm in the frame B, the deflection is caused in the middle, and it is forced downward (as shown in red, fig. 2) at the point where the said spring is connected with the valve.

The said valve, following the spring in its downward motion, is drawn into its seat, and the valve, thus closed, is perfectly tight, and will remain so as long as there is any steam in the cylinder A.

When the steam becomes condensed in the said cylinder, and the spring C cooled, it will contract, and open the valve, which will thus be in readiness for use when the steam is again applied.

I do not broadly claim the spring acted on and expanded by the steam, for the purpose of closing the valve; but

What I do claim as new and useful, and desire to secure by Letters Patent, is—

Inserting the frame B, which holds the spring C, into the case or cylinder A, by this means allowing the said cylinder to be constructed in one piece, and thereby doing away entirely with the use of packing.

MOSES P. BRECKENRIDGE.
